US0D1019578S

(12) **United States Design Patent** (10) **Patent No.:** **US D1,019,578 S**
(45) **Date of Patent:** **** Mar. 26, 2024**

(54) **CONTROLLER**

(71) Applicant: **ABB Schweiz AG**, Baden (CH)

(72) Inventors: **Chunping Zhang**, Shanghai (CN);
Yang Gao, Västerås (SE); **Fawei Zhang**, Shanghai (CN)

(73) Assignee: **ABB SCHWEIZ AG**, Baden (CH)

(**) Term: **15 Years**

(21) Appl. No.: **29/765,469**

(22) Filed: **Jan. 8, 2021**

(51) **LOC (14) Cl.** **13-03**

(52) **U.S. Cl.**

USPC **D13/162**; D13/162.1

(58) **Field of Classification Search**

USPC D13/162, 162.1, 163, 199

Primary Examiner — Selina Sikder

(74) *Attorney, Agent, or Firm* — Greenberg Traurig, LLP

(57) **CLAIM**

The ornamental design for a controller, as shown and described.

DESCRIPTION

FIG. 1 illustrates a front view of the controller.

FIG. 2 illustrates a rear side view of the controller shown in FIG. 1.

FIG. 3 illustrates a left side view of the controller shown in FIG. 1.

FIG. 4 illustrates a right side view of the controller shown in FIG. 1.

FIG. 5 illustrates a top view of the controller shown in FIG. 1.

FIG. 6 illustrates a bottom view of the controller shown in FIG. 1.

FIG. 7 illustrates a perspective view of the controller shown in FIG. 1; and,

FIG. 8 illustrates another perspective view of the controller shown in FIG. 1.

The broken lines in the drawing are for illustrative purposes only and form no part of the claimed design.

1 Claim, 8 Drawing Sheets
